United States Patent Office.

G. B. MASSEY, OF NEW YORK, N. Y.

Letters Patent No. 95,245, dated September 28, 1869.

IMPROVEMENT IN LOW-WATER DETECTORS FOR BOILERS.

The Schedule referred to in these Letters Patent and making part of the same.

To all whom it may concern:

Be it known that I, G. B. MASSEY, of the city of New York, in the county and State of New York, have invented a new and improved Low-Water Detector; and I do hereby declare that the following is a full, clear, and exact description thereof, which will enable others skilled in the art to make and use the same, reference being had to the accompanying drawings, forming part of this specification, in which—

Figures 1 and 2 are vertical sections of my improved low-water detector, showing the valve in different positions.

Similar letters of reference indicate corresponding parts.

This invention relates to a safety-attachment to steam-boilers, whereby an alarm will be instantly given as soon as the water sinks below a certain desired level.

The invention has for its object to construct an apparatus which will operate with certainty at low as well as high pressure.

The invention consists in an improved construction and arrangement of parts as will be hereinafter described.

A, in the drawing, represents a portion of a steam-boiler.

Into the boiler is fitted a preferably-vertical pipe B, whose lower end is about on a level with the low-water line, that is to say, with the line below which the water should not stand in the boiler. The pipe is open at its lower end, and is, above the boiler, fitted into the lower end of a vessel, C. This vessel is of cylindrical or other suitable shape, and supports a steam whistle, D, on its upper head.

The entrance to the steam whistle is to be closed by a valve, E, which is fitted upon a cylinder or other vessel, F.

The cylinder F is enclosed within the vessel C, and is smaller than the same, so that it can play up and

down therein, and to have an annular steam-passage, a, formed around it.

Lateral play of the vessel F is or may be prevented by arranging projecting ribs, or lugs b on its sides.

When the water in the boiler stands higher than the lower end of the pipe B, it will, by the pressure within the boiler, be forced into the pipe B and vessel C, to elevate the vessel F, which will float on the water, and will thereby hold the valve E against its seat, as in fig. 1. The valve will thus close the passage c to the steam whistle. As soon, however, as the water falls below the lower end of the pipe B, it escapes from the vessel C, and steam enters the same.

The vessel F will not float on the steam, but will drop so as to draw the valve down, as in fig. 2.

The steam will then enter the whistle and blow the alarm.

The valve, in order to always fit into the seat at high water, even if the vessel should be slightly displaced in a horizontal direction, is swivelled in the vessel F, with its shank d, and has a ball, e, at the lower end of the shank, so that it may swing in either direction.

The vessel F may, therefore, move slightly in a horizontal direction, when the valve is shut without drawing it out of its seat.

A vertical pipe may be arranged within the pipe B, to project into the vessel F, for the purpose of serving as a conveyer of steam into F, to the quicker expel the water.

Having thus described my invention, What I claim as new, and desire to secure by Letters Patent, is—

The float F and valve E, constructed and arranged with reference to the whistle D, cylinder C, and pipe B, substantially as herein shown and described.

G. B. MASSEY.
